UNITED STATES PATENT OFFICE

158,855

GAME DEVICE

Harmon H. Heidman, Brooklyn, N. Y.

Application March 8, 1948, Serial No. 144,971

Term of patent 7 years

(Cl. D34—5)

To all whom it may concern:

Be it known that I, Harmon H. Heidman, a citizen of the United States, residing at Brooklyn, in the county of Kings and State of New York, have invented a new, original, and ornamental Design for a Game Device, of which the following is a specification, reference being had to the accompanying drawing, forming a part thereof.

Fig. 1 is a top plan view of a game device, showing my new design.

Fig. 2 is a side view thereof.

Fig. 3 is a bottom plan view thereof.

I claim:

The ornamental design for a game device, substantially as shown.

HARMON H. HEIDMAN.
